UNITED STATES PATENT OFFICE.

OTTO KUBATZKY, OF TULSA, OKLAHOMA.

DESIGN FOR A SET OF PLAYING CARDS.

Application filed August 5, 1927. Serial No. 23,006. Term of patent 14 years.

To all whom it may concern:

Be it known that I, OTTO KUBATZKY, a citizen of the United States, residing at Tulsa, in the county of Tulsa and State of Oklahoma, have invented a new, original, and ornamental Design for a Set of Playing Cards, of which the following is a specification, reference being had to the accompanying drawing, forming part thereof.

The figures are elevations of the full face of a set of playing cards showing my new design.

I claim:

The ornamental design for a set of playing cards, as shown.

OTTO KUBATZKY.
